(57) **CLAIM**

The ornamental design for a vehicle wheel, as shown and described.

DESCRIPTION

FIG. 1 is a front right perspective view of a vehicle wheel constructed according to my novel design;

FIG. 2 is a front view thereof;

FIG. 3 is a front left perspective view thereof; and,

FIG. 4 is a left view thereof.

The broken lines showing of environmental structure in FIGS. 1-4 of the drawings are for illustrative purposes only and form no part of the claimed design.

A right side view has been omitted because this view is identical to the left view shown in FIG. 4.
